Assistant Examiner — Michelle M Reeves

(57) **CLAIM**

The ornamental design for a bathroom accessory, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a bathroom accessory, showing our new design;

FIG. 2 is another perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of the bathroom accessory of FIG. 1, shown in an environment of use;

FIG. 10 is a perspective view of the bathroom accessory of FIG. 1, shown in a different environment of use;

FIG. 11 is a perspective view of the bathroom accessory of FIG. 1, shown in another different environment of use;

FIG. 12 is a perspective view of the bathroom accessory of FIG. 1, shown in another different environment of use; and,

FIG. 13 is a perspective view of the bathroom accessory of FIG. 1, shown in another different environment of use.

The broken lines shown in the drawings depict portions of environment that form no part of the claimed design.
